UNITED STATES PATENT OFFICE.

JOSIAH A. DEWEY, OF SAN FRANCISCO, CALIFORNIA, ASSIGNOR TO WILLIAM K. WHITE, OF SAN FRANCISCO, CALIFORNIA.

DISAPPEARING BED.

1,097,751.

Specification of Letters Patent.

Patented May 26, 1914.

Application filed October 15, 1913. Serial No. 795,281.

To all whom it may concern:

Be it known that I, JOSIAH A. DEWEY, a citizen of the United States, and a resident of the city and county of San Francisco, 5 State of California, have invented certain new and useful Improvements in Disappearing Beds, of which the following is a specification.

The invention relates to that type of dis- 10 appearing bed more generally known as a wall bed.

The object of the invention is to provide a wall bed which may be turned to lie on opposite sides of a wall, and which is of sim- 15 ple and substantial construction.

The invention possesses other advanta- 20 geous features which with the foregoing will be set forth at length in the following description, where I shall outline in full that form of the invention which I have selected 25 for illustration in the accompanying drawings. The novelty of the invention will be included in the claims succeeding said description. From this it will be apparent that 30 I do not limit myself to the showing made by said drawings and description, as I may adopt many variations within the scope of my invention as set forth in said claims.

Referring to said drawings: Figure 1 is a 35 top or plan view of the bed of my invention showing the bed in the closet or recess, the dotted lines indicating the position of the bed after it has been turned through arcs of 90 and 180 degrees. Fig. 2 is a vertical section through the lower end of the bed supporting door or panel taken on the line A—A Fig. 1. Fig. 3 is a perspective view of 40 a portion of the rack carrying plate. Fig. 4 is a detail showing a modified form of rack. Fig. 5 is a detail showing a modified form of 45 construction. Fig. 6 is a top or plan view of a modified form of construction in which the center of rotation of the bed is movable in the direction of the depth of the closet; the 50 full lines indicating the position of the bed in the closet, and the dotted lines indicating the position of the bed in the room. Fig. 7 is a view of the part of the panel adjacent to the center of rotation showing the two extreme 55 positions of the panel.

The opening in the wall 2 through which the bed moves, may serve as a means of communication between two apartments, so that the bed may be used in either apartment, 55 or it may be the opening of a closet or recess,

so that when the bed is not in use, it lies in the closet. It is understood that the bed is of the foldable type, which, when folded, is vertically disposed and which is moved to the horizontal when it is to be occupied. 60 When the bed is being moved through the opening or when it is in the closet, it is in the folded position.

The bed frame 3 is mounted by suitable means on a panel 4, in such manner that 65 when the bed is folded, the center of gravity of the bed lies between its pivotal point of attachment to the panel and the panel, so that there is no tendency for the foldable part of the bed to fall down. The panel 4 is 70 of slightly less width than the opening and when the bed is in the closet lies substantially flush with the outer surface of the wall 2. The panel is arranged so that it may be turned to cause that side to which the bed is 75 attached to face the room so that the bed may be used.

Arranged below and above the panel, on the floor and door framing or building structure respectively, are toothed elements, preferably in the form of racks 5, which are engaged by gears or segmental gears 6 securely attached to the panel at the bottom and top, by any suitable means, such as the flange 7, formed integrally with the gear. 80 Each gear is held in mesh with its respective rack by means of a backing plate 8 paralleling the rack 5 and with which the centrally placed boss 9 on the gear engages. The boss 9 on the lower gear is rounded on the lower end to reduce the area of contact 85 between the boss and the bearing plate 12, thereby reducing the frictional resistance to turning. The rack 5, the backing plate 8 and the bearing plate 12 are preferably 90 formed integrally as shown in Fig. 3. In such construction these elements form parts of the plate 13 and the backing plate and bearing plate combine to produce a slot 14 95 in which the boss 9 is disposed.

The rack 5 is slightly longer than one-half the circumference of the gear 6, and in the construction illustrated in Figs. 1 to 5 inclusive is arranged transversely of the opening of the wall and lies substantially midway between the sides of the opening. The gear 6 is arranged to one side of the center of the door or panel, so that when the door or panel is in either of its extreme 105 positions, the gear engages with the end of 110

the rack. The center of rotation of the gear 6 or the boss 9 is preferably arranged behind the panel when the panel is in such position that the bed is in the closet. As the 5 panel is turned, therefore, to bring the bed into the room, the gear travels along the rack to the opposite end, and when the panel is turned through an arc of 180 degrees, the major portion of the gear 6 lies in front of 10 the panel. The panel is, therefore, not reversible in the opening, but in one position lies substantially flush with the face of the wall and in the other position is displaced backward and lies behind the face of the 15 wall. This backward movement of the panel causes the bed to lie closer to the wall when it is in a horizontal position, so that it occupies less room space. When the bed is in the horizontal position the head of the bed 20 lies substantially flush with the wall, so that the person sleeping in the bed does not lie with his head within the recess. By placing the gear 6 off center with respect to the panel and adjacent that edge of the panel 25 which moves into the closet when the panel is turned, the smaller part of the panel extends into the closet and the closet may be made more shallow than is possible with a centrally pivoted panel or a reversible panel.

30 In Fig. 4, I have shown a modified form of rack 5 which causes a forward movement of the center of rotation of the panel during its initial turning movement from the closed position. By closed position, I 35 mean the position of the panel when the bed is in the closet. The rack is formed with a forwardly extending part 15 and a transversely extending part 16, so that the initial movement of the panel causes a simultaneous forward and transverse movement of the center of rotation of the panel, allowing the closet to be made more shallow 40 and causing the panel, in its open position, to lie closer to the face of the wall. By 45 open position of the panel, I mean the position of the panel when the bed is in the room.

In Fig. 5 I have shown a construction in which the backing plate 8, which operates 50 to hold the gear 6 in engagement with the rack 5, is displaced by a gear 17 meshing with gear 6, and a fixed rack 18 screwed to the floor or otherwise held in place, arranged parallel to the rack 5 and in engagement 55 with gear 17. The intermeshing of the racks and gears prevents a transverse movement of one gear with respect to the other, so that the gears are always held in mesh and move transversely simultaneously, thereby holding 60 gear 6 in mesh with rack 5.

In Figs. 6 and 7 I have shown a construction in which the rack 5 is arranged in the direction of the depth of the closet instead of transversely thereof. The gear 6 is 65 placed to one side of the transverse center

of the panel so that the opposite ends of the panel swing through arcs of different radii as the panel is turned. When the panel is in the closed position, the gear engages the rear end of the rack and travels 70 forward on the rack as the panel is moved to the open position. The gear is placed, so that as the panel is turned, the shorter side of the panel moves backward into the closet, and by varying the position of the gear between the center and the end of the panel, 75 different lengths of panel will swing into the closet, so that the construction may be adapted to closets of various depths. When the panel is in the open position, it lies in front of the wall and partly to one side of the opening therein, thereby allowing a free 80 passage into the closet. This feature is advantageous in that it permits of entrance to the closet during the time that the bed 85 is in the room.

I claim:

1. The combination with a wall having an opening, of a panel adapted in one position to close said opening, a toothed element attached to said panel to one side of the transverse center thereof and a fixed toothed element in mesh with said first named toothed element.

2. The combination with a wall having an opening, of a panel adapted in one position to close said opening, a gear attached to said panel to one side of the transverse center thereof, and a fixed rack engaged by said gear.

3. The combination with a wall having an opening, of a panel adapted in one position to close said opening, a gear attached to said panel to one side of the transverse center thereof, a fixed rack engaged by said gear, 105 and means for holding the gear in engagement with said rack.

4. The combination with a wall having an opening, of a panel adapted in one position to close said opening, a gear secured to said 110 panel to one side of the transverse center thereof, a fixed rack engaged by said gear, a central boss on said gear, and a backing plate arranged parallel to said rack arranged to engage said boss and hold the gear in mesh 115 with said rack.

5. The combination with a wall having an opening, of a panel adapted in one position to close said opening, a gear attached to said panel to one side of the transverse center 120 thereof, a fixed rack engaged by said gear arranged transversely of the opening, and means for holding said gear in mesh with said rack.

6. The combination with a wall having 125 an opening, of a panel adapted in one position to close said opening, a gear attached to said panel to one side of the transverse center thereof, a fixed rack arranged transversely of said opening, the ends of said 130

rack being substantially equally spaced from the sides of said opening, and means for holding the gear in mesh with said rack.

7. The combination with a wall having an opening, of a panel adapted in one position to close said opening, a gear attached to said panel to one side of the transverse center of said opening, and means operative by the rotation of the panel for moving said gear to the other side of the opening.

8. The combination with a wall having an opening, of a panel adapted in one position to close said opening, a gear attached to said panel to one side of the transverse center of said opening, and means operative by the rotation of the panel for moving said gear forwardly and transversely to the other side of said opening.

9. The combination with a wall having an opening, of a panel adapted in one position to close said opening, a gear secured to said panel and a fixed rack engaged by said gear having a portion extending transversely of the opening and a portion arranged at an angle to said transverse portion.

10. The combination with a wall having an opening, of a panel adapted in one position to close said opening, vertical pivots on which said panel is mounted, said pivots being arranged at one side of the transverse center of the panel, and means operative by the rotation of the panel for moving said pivots in the direction of the depth of the opening.

11. The combination with a wall having an opening, of a panel adapted in one position to close said opening, a gear attached to said panel to one side of the transverse center thereof, and a fixed rack arranged in the direction of the depth of the opening, engaged by said gear.

12. The combination with a wall having

an opening, of a panel adapted in one position to close said opening, a gear attached to said panel to one side of the transverse center thereof, a fixed rack arranged in the direction of the depth of the opening engaged by said gear and means for holding said gear in engagement with said rack.

13. The combination with a wall having an opening, of a panel adapted in one position to close said opening, attached to a vertical axis arranged at one side of the transverse center of said panel and movable in the direction of the depth of the opening.

14. The combination with a wall having an opening, of a panel adapted in one position to close said opening attached to a vertical axis arranged adjacent one side of the opening and intermediate between the sides of the panel, and means operative by the movement of the panel about said axis to move said axis in the direction of the depth of the opening.

15. The combination with a wall having an opening, of a panel adapted in one position to close said opening, a toothed element attached to said panel, and a fixed toothed element in mesh with said first named toothed element.

16. The combination with a wall having an opening, of a panel adapted in one position to close said opening, a gear attached to said panel, a fixed rack engaged by said gear, and means for holding said gear in mesh with said rack.

In testimony whereof, I have hereunto set my hand at San Francisco, California, this 10th day of October, 1913.

JOSIAH A. DEWEY.
